J. H. O'NEILL

METHOD AND MEANS OF PRODUCING HEAT

Filed Dec. 5, 1919

Inventor
John Hugh O'Neill
By *Anthony J. O'Neill* His Attorney

UNITED STATES PATENT OFFICE.

JOHN HUGH O'NEILL, OF SPRINGFIELD, MISSOURI.

METHOD AND MEANS OF PRODUCING HEAT.

Application filed December 5, 1919. Serial No. 342,833.

To all whom it may concern:

Be it known that I, JOHN HUGH O'NEILL, a citizen of the United States, and resident of Springfield, Missouri, have invented new and useful Improvements in Methods and Means of Producing Heat away from atmospheric air, which are fully set forth in the following specification and which are a continuation of the basic invention disclosed 5 in my application Serial No. 269,268, filed January 2, 1919, entitled Method and means of generating power, and also disclosed in other applications filed concurrently here- 10 with, and bearing Serial Numbers 342,832 and 342,834.

The applications referred to relate to the combustion of metal or other fuel, away from the oxygen of the atmosphere, by combining it with a stored combustion support- 20 ing gas or a carrier of such gas or gases; the fuel to be either stored in the combustion chamber and the comburent introduced as desired or both elements introduced simulta- 25 neously.

The present application covers a class of new and definite methods which are an improvement on the process known as the thermit reaction in which the comburent and the fuel metal are both dry, in a finely di- 30 vided state, and intimately mixed.

The invention consists primarily in the method and means of producing heat by first mixing together a fuel or fuels with one or more suitable comburents then introducing 35 the mixture at a governed rate into a suitable combustion chamber with or without modification of the mixture by the injection of water or any other comburents as the mixture approaches the combustion 40 chamber.

Further features of the invention consist in the use of liquid and solid fuels, of liquid and solid comburent, in the arrangements for introducing the elements of com- 45 bustion, in the regulation and disposal of the combustion products, in the types of combustion chambers or furnaces used, and in the means of bringing the system immedi- 50 ately to operating heat and condition.

Another feature of the invention consists in using a carrier or mixture of carriers of combustion sustaining gas or gases which are in whole or in part liquid or liquefiable, with a fuel or mixture of fuels which are in whole or in part liquid or powdered or in the form of grains. Both elements may be

mixed together into a liquid or mush or paste which can be conveyed, pumped ex- 60 truded or otherwise conveniently introduced at a governed rate, into a combustion cham- 65 ber where they react with the production of heat away from atmospheric air. This heat can be applied to any desired use such as heating a furnace, producing a motive fluid, or manufacturing water gas or other gases. 70 The reaction can very conveniently be car- 75 ried on under pressure since all the neces- 80 sary combustion materials are in a compact liquid or solid form and the changing in whole or in part to the gaseous state as a 85 result of the reaction may be made to yield 90 any desired pressure.

In the production of motive fluid or of water gas or in similar processes the react- 95 ing mixture may be composed of a fuel or 75 fuels in liquid, granular, pulverized, or other form and with a carrier or carriers which contain part or all of the combustion sustaining gas. A sufficiency or a super- 80 fluity of water, or solution of gas carrier, 85 may be added in the form of vapor or liquid between the pump and the combustion chamber, thus making sure that oxygen is 90 supplied to the reaction in not less than equivalent proportion without making the 95 mixture too wet for convenient handling and also insuring that the reaction does not travel back through the introducing pipe and devices to the storage container.

Fuels may be any material that will react 90 with a positive heat value such as the alkali and alkali earth metals, lithium, rubidium, potassium, barium, strontium, sodium, boron, calcium, silicon, magnesium, aluminum, etc., carbons such as charcoal, coal or coke, 95 hydrocarbons including gases that can be stored as liquids under pressure, animal, vegetable and mineral oils, fats, waxes, and tars, spirits, alcohols, ethers, esters, naphtha, gasoline, acetone, solutions of acetylene in 100 acetone, sulphur, phosphorus, sugar, shellac, glucose, etc. Some of these fuels are solid and may be reduced to fluid or mush form by grinding, by solution, or by heat, or by 105 a combination of these methods.

Combustion supporting gas carriers or comburents include a very large number of compounds the principal of which are com- 110 pounds of oxygen or chlorine. Hydrogen, nitrogen, fluorine, bromine are of much less importance except where combined with oxygen or chlorine or both. Among the

most useful combustion supporters are the oxides of metals, including the peroxides of potassium, sodium, calcium, magnesium, barium, strontium, lithium, manganese, and the heptoxide of manganese, also the nitrites and nitrates including ammonium nitrate, nitrates of above named metals, nitrite and nitrate of iron, also the chlorates and sulphates. The most useful combustion supporters are the liquid gas carriers such as water, hydrogen peroxide, nitrogen tetroxide, nitric acid, hydrochloric acid, sulphuric acid, etc.

In the manufacture of water gas the blowing up of the fire may be dispensed with by feeding in a metal or metallic substance or alloy having a plus heat reaction with water, along with a carbon or hydrocarbon in such proportion that the loss of heat in decomposing water and transferring its oxygen to form carbon monoxide will be approximately balanced by the plus heat of the metal reaction. This would also yield hydrogen gas to the mixture.

In applying my method of producing heat for the production of a motive fluid, a typical reaction is that between ammonium nitrate and an alloy of magnesium and aluminum

with a resultant plus heat value of 2263 calories per gram or 4073 B. T. U. per pound of materials which allows of a large heat value to vaporize water. The nitrogen and hydrogen may be vented outside the boiler through a feed water heater and the heat of the reaction transferred through a transfer wall to water, thus making a straight steam cycle; or the gases may be vented into the steam space making a gas-steam cycle.

For bringing this system into operative condition, a calculated amount of thermit may be used and this may be ignited by any of the usual methods such as the electric spark or the percussion cap. For instantaneous delivery of power from a cold system a nitrate thermit is well suited. It is particularly rapid because the gaseous waste products which may be nitrogen or a mixture of nitrogen and hydrogen, or a mixture of nitrogen, hydrogen and steam, are immediately available in calculated quantity as motive fluid.

The fuels, oxygen carriers or other combustibles and cycles can be varied and combined in almost innumerable ways without departing from the spirit of my invention. One arrangement of the apparatus for carrying out my invention is illustrated in the accompanying drawings in which

Fig. 1 is a diagrammatic view in longitudinal section showing one arrangement of

the apparatus, and Fig. 2 is a detail showing an alternative construction for a part thereof.

In the drawing 1 is a steam boiler surrounding a steam space 2 between a heater 70 pot, or fire tube 3 which encloses the refractory lined combustion chamber 4. The boiler 1 is provided with gland packings at 5 and 6. In the combustion chamber 4 there is a container 7 made of aluminum or other 75 combustible metal or material, and filled with a thermit mixture. The thermit in the container 7 is adapted to be ignited by a percussion charge 8 which may be detonated by a firing pin 9.

A container 10 for combustible mixture or mush is provided with a plunger 11 operated by a screw 13 which screw has an agitator 12 secured thereto. The screw 13 is rotated by any suitable means, a gland packing 14 being provided to prevent leakage along the screw. The container 10 is surrounded by a jacket 15 for supplying heat to the mixture. The plunger 11 forces the fuel mixture from the container 10 90 through the tube 16 to the combustion chamber 4 at a rate determined by the speed of rotation of the screw 13.

In operation the firing pin 9 detonates the percussion charge 8, the thermit combusts, the container 7 melts and combusts, the hot gases disrupt the seal 17 by heat or pressure and pass to the steam space 2, then to the steam collector or dryer 18, and thence through a pipe 19 to a prime mover. The prime mover may drive the screw 13 through suitable transmission devices to move the plunger piston-wise. The fuel mixture will constantly enter the combustion chamber through the tube 16 and thereby continuously support combustion. The feeding mechanism illustrated diagrammatically by 13 and 11 may be driven at any fixed speed, at the prime-mover speed 95 or at any other desired or varied speed and the changes in the speed thereof may be accomplished by any suitable manual, or automatic means. This rate may be regulated 100 by the pressure in the boiler or may be so operated that it will be the equivalent of a 105 throttle on the prime mover.

A water pump 20 is driven by the prime-mover or by other means at any regulated or varied speed, automatically regulated or otherwise. It supplies water through the tube 21 to the boiler at 22 and also if desired, to the fuel admission tube at 23. The amount of water admitted to the fuel may be manually regulated by a valve 24 to a fixed calibrated amount proportionate to the fuel used, or it may be automatically controlled 110 by pressure or by temperature or both.

The feed-water passing through pipe 21 is preheated in the gas collector 25 which is supplied with water or steam circulating 115

through the pipes 26 and 27 connected with the boiler. The relatively cooler feed water causes the collection of non-condensable gas or air at boiler pressure. This gas passes 5 through the tube 28 to the fuel container 10, thus equalizing the pressure in fuel container and combustion chamber

Fig. 2 shows one of many possible alternative expedients for the pumping of the 10 fuel to the combustion chamber in which 29 is the pump driven by any suitable means, and 30 is an agitator, for effectively breaking up any lumped or caked masses of the fuel.

15 What I claim is:

1. The method of producing heat away 20 from atmospheric air which consists in mixing a pulverized fuel with a normally solid combustible applying heat to the mixture to melt the combustible and reduce the mixture 25 to a soft mushy condition, conveying the soft mixture at a governed rate to a combustion chamber which has been previously heated to temperature above the ignition point of the mixture.

2. The method of producing heat away 30 from atmospheric air by burning at a desired rate a fuel with a combustible, in which said fuel and said combustible are mixed and stored in a container, applying heat to the mixture so as to soften it, conveying the soft mixture at a governed rate from said container through a connection to a combustion chamber which has been previously heated 35 to a temperature above the ignition point of the mixture, introducing water or other liquid into the mixture so as to thin said mixture, add combustible, and control the temperature of the combustion.

40 3. The method of producing a motive fluid away from atmospheric air which consists in

mixing a fuel with a combustible to form a wet, soft or mushy mixture, starting combustion in a chamber to produce a temperature sufficient to start combustion of said mixture, feeding said mixture at a governed rate to said combustion chamber, applying the heat from said combustion chamber to a body of water for the purpose of vaporizing the water and superheating the resulting steam, and mixing the gaseous products of combustion with said steam to further superheat the same and to form a mixed motive fluid.

4. An apparatus for generating motive 55 fluid away from atmospheric air including a shell forming a boiler, a structure within said shell and spaced away therefrom to form a water and steam space, means including a charge of highly inflammable material for starting combustion in said chamber, a container adapted to hold a mixed fuel and combustible, means for heating said container to keep the fuel mixture in a soft or mushy condition, means for extruding 60 the mushy fuel from said container to said combustion chamber.

5. An apparatus for generating motive 65 fluid including a shell forming a boiler, a structure forming a combustion chamber 70 located therein and spaced away from the shell to form a water and steam space, means for initially starting combustion in said chamber, a fuel container, means for extruding fuel from said container into said 75 combustion chamber and means for supplying a regulated quantity of water to the fuel as it is being extruded.

In witness whereof I have hereunto signed my name.

JOHN HUGH O'NEILL.
